(57) **CLAIM**

The ornamental design for a cooling apparatus as shown and described.

DESCRIPTION

FIG. 1 is a perspective view of a cooling apparatus according to the claimed design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is another perspective view thereof depicting the cooling apparatus in a position of use.

The broken lines in the drawings illustrate portions of the cooling apparatus and its environment, which form no part of the claimed design.

1 Claim, 6 Drawing Sheets(56)
